Des. 237,482
Patented Nov. 4, 1975

237,482

ANCHOR POST FOR VEHICLE BODY OR FRAME STRAIGHTENING APPARATUS

William J. Meis, 3636 Camerino St.,
Lakewood, Calif. 90712

Filed Apr. 29, 1974, Ser. No. 465,294

Term of patent 14 years

Int. Cl. D12—16

U.S. Cl. D12—155

FIG. 1 is a perspective view of an anchor post for vehicle body or frame straightening apparatus showing my new design;

FIG. 2 is a side elevation view thereof as viewed from the right of FIG. 1;

FIG. 3 is a top plan view thereof; and

FIG. 4 is a bottom plan view thereof.

I claim:

The ornamental design for an anchor post for vehicle body or frame straightening apparatus, as shown.
